DUAL FREQUENCY ANTENNA ARRAYS

Thomas A. Marshall, San Diego, Calif.

Application November 14, 1952, Serial No. 320,633

4 Claims. (Cl. 343—815)

(Granted under Title 35, U. S. Code (1952), sec. 266)

The invention described herein may be manufactured and used by or for the Government of the United States of America for governmental purposes without the payment of any royalties thereon or therefor.

This invention relates to antennas and more particularly to antennas for the reception of high frequency signals such as are utilized for television transmission.

Television signals are broadcast at present over a number of frequency ranges or channels. It is desirable to provide television receivers adapted to receive signals transmitted on any of the channels used. The strength of signals obtained on any channel, however, is controlled in the first instance by the antenna which intercepts the signals and translates them to the television receiver. Antennas used for reception of signals from distant transmitting stations at present are of several types. The best of these types have either a high gain at a single frequency or a low gain at two or more frequencies. In the instant invention, the shape, number, and relative position of the active and inactive elements of the antenna are so disposed that extremely high gain is realized at two separated frequency bands with a fair gain at intermediate frequencies.

One of the objects of the invention is to provide a broad picture frequency response antenna which enables the array to be operated in or near resonance with the picture frequency.

It is an object of the invention to provide a new and improved television receiving antenna which provides a large voltage at its output terminals.

Another object of the invention is to provide an antenna array having a high gain on a low frequency channel and a high gain on a high frequency channel.

Other objects and many of the attendant advantages of this invention will be readily appreciated as the same becomes better understood by reference to the following description.

Fig. 1 is a diagram of the field pattern of a dipole at a frequency three times the fundamental of the antenna frequency;

Fig. 2 is a diagram of the field pattern of a V-shaped dipole;

Fig. 3 is a perspective view of the elements in an antenna embodying the invention;

Fig. 4 is a diagrammatic sketch of a modified form of the invention; and

Fig. 5 is a diagrammatic sketch of a further modified form of the invention.

The operation of all types of antennas, no matter how simple or complex their construction, is based upon the principles of the fundamental folded antenna whose physical length is equal to approximately one-half the wavelength of the signal to be transmitted or received. A convenient equation for computing the length of the fundamental folded antenna is

$$L = \frac{5640}{F}$$

2

where L is the length of the antenna in inches and F is the frequency in megacycles per second. The constant in the equation has been determined experimentally and makes allowance for the capacitance effect at the ends of the antenna in the television range of frequencies.

For receiving signals from a nearby source at several frequencies, a folded dipole cut to the proper length is fairly effective. The ability to receive signals from a distant station may be enhanced by a series of directors and reflectors or in yagi arrays which are among the best antennas for fringe areas. Yagi arrays, however, function for a single frequency only. It is obviously impracticable to have one antenna for each of the several channels that may be received in many localities.

A simple folded dipole properly cut for channel 4, which has a picture frequency of 67.25 mc., will also gather in signals on channel 11 having a picture frequency of 199.25 mc. This is so because the length in inches for a folded dipole for channel 4 equals

$$\frac{5640}{mc.} \text{ or } 82.37 \text{ inches}$$

and a long antenna consisting of a number of half-wave dipoles will provide considerable power gain over a half-wave dipole. Hence, the picture frequency for channel 11 is approximately equal to three times the fundamental resonant frequency of channel 4 and will be received on the same antenna. The calculated length of a dipole for channel 4 is 82.37 inches which is close to that of a three half wave dipole for channel 11 at 83.41 inches.

The field pattern for an antenna operating at a frequency three times the fundamental is shown in Fig. 1 wherein arms 10 and 12 of the folded dipole are arranged in a straight line.

35 If the antenna of Fig. 1 is modified so the free ends of the dipole are protruded forward to an angle of approximately 72 degrees or 144 degrees across the V-portion, the field patterns of the two end sections 14 and 16 will combine to produce a bi-directional lobe as shown in Fig. 2. An antenna having such a symmetrical V-shaped element has sufficient gain for nearby stations and the configuration produces a broad response. For fringe areas, however, additional elements are required to gather in the weak signals available.

40 In Fig. 3, a useful gain on channels 4 and 11 is obtained when element 18 is added to dipole 20. The length of element 18 is slightly less than that of dipole 20. Both elements are operated at or near resonance so there is maximum energy transfer between elements. This relationship is unlike that obtaining in yagi arrays which have straight elements with the parasitics operated off resonance. Additional elements 22 and 24 may be added to provide still more gain. The length of all elements ahead of the dipole is preferably about 0.987 times the length of the dipole. The optimum spacing between the various forward elements is approximately 0.104 times the wavelength of the low frequency channel. Element 26 may be added to the rear of dipole 20 to provide additional gain. The optimum spacing between dipole 20 and rear element 26 is approximately 0.094 times the wavelength of the low frequency channel. The free ends of element 26 are placed close to the free ends of dipole 20 in order to provide coupling since there is little gain, through the action of the rear element, on high frequencies unless such coupling is present. Element 26 must be cut slightly longer than dipole 20 to allow for adjustment of the free ends. It has been found that an increase in length of 4% over the length of the dipole works very well. The spacing between the V-sections is a compromise for obtaining optimum gain and best picture performance on both channels. The gain of

the above described antenna on channel 4 was found to be 2.0 over a five-element yagi array designed for that channel; on channel 11, the gain was 1.7 over a four element yagi array designed and mounted for optimum performance on that band. The elements of the antenna are preferably arranged in a horizontal plane parallel with the ground plane and having the open part of the V-shape facing the source of signals to be received. The elements may be supported by any conventional type of supporting means such as a horizontal boom clamped to a vertical mast (not shown). The output terminals of dipole 20 are provided with conductors 28 and 30 of a transmission line. The inner active element ends of dipole 20 and conductors 28 and 30 are, of course, insulated from the other elements and from the supporting members.

The size and spacing of the tubing for dipole 20 depends upon the impedance of the transmission line. Tubing having an outer diameter of $\frac{3}{4}$ inch for the paralleled portion and an outer diameter of $\frac{5}{16}$ inch for the active arms with a center-to-center separation of parallel and active arms of $2\frac{1}{2}$ inches has been found to give a good match to 300 ohm transmission line. The active and parallel arms of dipole 20 are preferably aligned in a vertical plane. The diameter of elements 18, 22, 24 and 26 may conveniently be $\frac{3}{4}$ inch. The horizontal plane including the inactive elements should be centered between the active and parallel arms of dipole 20; this refinement results in an appreciable gain.

Fig. 4 shows the spacing arrangement for a dual frequency array for channels 2 and 7. The proportions are similar to those of the antenna shown in Fig. 3 and corresponding elements have been given like numbers. The length of the dipole corresponds to the optimum length for channel 7 which is 96 inches for a folded antenna that can be operated on its third harmonic. The array may be designed to give a higher gain on one channel than on the other. This may be desirable in case the transmitting station on one channel is much more powerful than the station on the other channel. Arrays may be readily designed for other combinations of channels such as 3, and 8, 3 and 9, 4 and 12, and 5 and 13.

In Fig. 5, a tetra-channel array is shown. It is derived by combining two dual frequency arrays. Dipole 30 is resonant to channels 5 and 13, and dipole 32 is resonant to channels 4 and 11. Each dipole is provided with a separate transmission line which is connected to an antenna transfer switch located at the receiver. A tetra-channel array will provide higher gain over all four channels than a yagi antenna on any single channel. The gain at one frequency may be increased, at the expense of gain on the other channels, by adjusting the relative lengths and spacings of the inactive element. When dipole 30 is in use, the forward elements are the shorter tubes 34 and 36 while the rear elements 38, 40, 42 and dipole 32, acting as an inactive element, are all longer than the dipole in use. When dipole 32 is connected to the receiver, the five active elements ahead of it all contribute to an increase in gain.

Obviously many modifications and variations of the present invention are possible in the light of the above teachings. It is therefore to be understood that within

the scope of the appended claims the invention may be practiced otherwise than as specifically described.

What is claimed is:

1. An antenna for television reception comprising a folded dipole the arms of which diverge forwardly at an angle of approximately 144 degrees to each other, a plurality of elements located forwardly of said dipole each having arms diverging forwardly at about the same angle of the dipole arms, and an element located rearwardly of said dipole and having arms diverging forwardly at a smaller angle than said dipole arms, said elements and said dipole lying in a common plane.
2. A television antenna comprising a folded dipole having the two sides in a symmetrical V-shape with an included angle of 144 degrees and adapted to resonate at one television frequency and at harmonics thereof, a plurality of forward elements each having two sides substantially parallel with the sides of said dipole, the forward elements having a length slightly shorter than said dipole and having a distance between said dipole and the nearest forward element and between forward elements of approximately 0.1 times the wave length of the low frequency to be received.
3. The invention defined in claim 2 comprising in addition a V-shaped rear element cut slightly longer than and disposed rearwardly of said dipole, said rear element having an included angle of less than 144 degrees whereby coupling between the free ends of said rear element and said dipole is accomplished, the distance between the apices of said dipole and said rear element approximately equal to 0.09 times the wave-length of the low frequency to be received.
4. A tetra-channel antenna array comprising a forward dipole having the free ends protruded forwardly in a horizontal plane to form a V-shaped 144 degree angle, a rear dipole having arms substantially parallel to said forward dipole, a plurality of elements generally parallel to and disposed forward of said forward dipole, a plurality of similar elements disposed to the rear of said forward dipole, means for connecting a first transmission line to said forward dipole, and means for connecting a second transmission line to said rear dipole whereby the action of the dipole selected for reception of signals will be enhanced by said elements and by the other dipole acting as an addition element.
